PUMP JACK CIRCUIT

Harry F. Vickers, Detroit, Mich., assignor to
 Vickers, Incorporated, Detroit, Mich., a corpora-
 tion of Michigan

Application February 18, 1938, Serial No. 191,189

4 Claims. (Cl. 121—158)

This invention relates to a hydraulic control circuit for hydraulically actuated mechanisms.

An object of the invention is to provide an accurate time control for a cylinder pump jack or ram which is, in general, moved in one direction by pump pressure and in the opposite direction by gravity.

A further object is to provide a hydraulic means whereby the length of the stroke of the ram in either direction is accurately adjustable.

The invention may be applied to a fully automatic and continuous hydraulic system and the control units are so arranged that they are mechanically independent of the main jack cylinder and may control it from a remote position.

Other features of the invention have to do with the combination of the hydraulic control with accurate adjustable flow control and time delay devices and with other details of construction as will be brought out in the following description and claims.

Certain constructions in accordance with the invention are illustrated by way of example, in the accompanying drawings, in which:

Fig. 1 is a cross section of a time lag device to be used in the control circuit, all the passage-ways being shown in the same plane for purposes of illustration.

Fig. 2 is a diagrammatic presentation of the circuit of one modification of the invention utilizing a piston-cylinder time control.

Fig. 3 illustrates a modified diagrammatic circuit wherein the time lag device of Fig. 1 is used.

Figs. 4 and 5 illustrate sectional views of the four-way valves of Fig. 2.

Referring to Fig. 2, the main elements of the circuit consist of a constant delivery pump 5, a hydraulic ram or jack 6 and a piston 7, a timing cylinder 8, and a series of valves interconnected by hydraulic conduits. The valves in the system consist of a relief valve 9, a check valve 10 which serves as a low pressure relief valve, a globe or throttle valve 11, two pilot operated four-way valves 12 and 13, a pilot valve 14, and a flow control valve 15. This flow control valve is of the type disclosed in British Patent No. 399,609, of June 11, 1932.

The conduits of the system which interconnect the various elements of the system and lead to and from a tank 16 will be described in connection with the detail description of the circuit. Pressure for raising the ram 7 is supplied by the pump 5 to the cylinder 6 through the relief valve 9, the low pressure relief valve 10, and the pilot operated four-way valve 12. The low pressure

5 relief valve 10 is equipped with a spring which maintains a low back pressure sufficient to operate the pilot control system and this valve also prevents the load from falling in case of power failure during hoisting. The four-way valve 12, which is shifted by pilot pressure, controls the direction of movement of the main cylinder and directs the pump delivery either to the cylinder 6 or to the tank. During the lowering of the ram, liquid from the cylinder 6 is directed to the tank through the globe or throttle valve 11. The ram piston 7 is lowered by gravity and the rate of the lowering is adjusted by the globe valve 11, the upper rate of the ram being constant under 10 the delivery of pump 5.

An auxiliary control for determining the length of the stroke of the ram 7 is provided by the timing cylinder 8, pilot operated four-way valve 13, pilot valve 14, and the flow control valve 15. Branching off from a conduit 17 between two 15 valves 9 and 10 is a pilot pressure conduit 18 which leads to the four-way valve 13. This valve is adapted to direct pilot pressure to either end of the cylinder 8 depending on the position in which the valve is shifted. Conduits 19 and 20 lead to the timing cylinder 8 while conduits 21 and 22 connect the conduits 19 and 20 respectively with opposite ends of the pilot operated valve 12. A piston 23 within the timing cylinder 20 is provided with piston rods 24 and 25, the latter being provided with adjustable dogs 26 and 27 which operate the pilot valve 14 by engaging fingers 28 and 29 of the pilot valve. Dog 26 and finger 29 are in one plane while dog 27 and finger 28 are in another. A conduit 30 directs pressure from the pilot pressure conduit 18 to the pilot valve 14 and conduits 31 and 32 lead from the pilot valve 14 to the respective ends of the four-way valve 13. A conduit 33 connects the 25 valve 13 with the flow control valve 15 which in turn is connected to the tank through conduit 34.

The cycle of operation of the circuit of Fig. 2 is as follows: Assuming that the dog 26 has just shifted the finger 29 of the pilot valve 14 clockwise, pilot pressure is directed from the pump 5 through conduits 17, 18, 30 and 31 to the lefthand side of the four-way valve 13. This valve is shifted by this pilot pressure (see Fig. 4) so that the righthand side of the timing cylinder 8 is 30 connected to the conduit 18 and the lower side of the four-way valve 12 is also open to the pilot pressure through conduit 22. By reason of this pressure in conduit 22, the valve 12 is shifted (see Fig. 5) so that the main cylinder 6 is open to the tank through the throttle valve 11. The pump

delivery is returned to the tank at the low back pressure caused by the valve 10 and passes through the valve 12 to a conduit 35. While the timing piston 23 is being moved to the left by the pilot pressure, the main ram 7 lowers by gravity.

When the dog 27 shifts the levers of the pilot valve 14 counterclockwise, pilot pressure is directed to the righthand side of the four-way valve 13, shifting the same so that the pilot pressure from the conduit 18 is directed to the lefthand side of the timing cylinder 8 through the conduit 19 and to the upper side of the four-way valve 12 through the conduit 21. This latter valve is shifted so that the delivery of the pump 5 is directed to the main cylinder 6 so that the pump pressure is built up to raise the ram 7. While the timing piston 23 moves to the right the ram 7 is elevated by the pump pressure. When the piston 23 reaches the end of its stroke, to the right, the pilot valve 14 will again be shifted in the clockwise direction so that the four-way valve 12 will be reversed and a cycle will start to repeat.

It will be seen that in this circuit of Fig. 2 the piston 7 in the main cylinder reverses at the same time that the timing piston 23 reverses, so that by adjusting the stroke time of the timing cylinder 8, the length of the stroke of the piston in the main cylinder 6 may be accurately controlled. The adjusting of the stroke time of the timing cylinder 8 is accomplished by reason of the fact that when the pilot pressure is being directed from the conduit 18 to one end of the timing cylinder 8, the other end of the cylinder will be connected through the four-way valve 13 and the conduit 33 to the adjustable flow control valve 15. With this arrangement the stroke time of the piston 23 can be accurately determined. The length of the stroke of the main cylinder is consequently controlled by the flow control valve 15 since pressure fluid is supplied to the main cylinder at a constant rate. The stroke time of the timing cylinder 8 may also be varied by adjusting fingers 26 and 27 closer together or farther apart.

The modification shown in Fig. 3 is adapted to perform the same functions as that shown in Fig. 2 but the circuit for accomplishing these results is considerably different. Referring to Fig. 3, the main elements of the system consist of the pump 5, cylinder 6 and ram 7, high pressure relief valve 36, low pressure relief valve 37, throttle valve 38, two pilot operated four-way valves 39 and 40 and timing valves 41 and 42. The valves 36 and 37 of Fig. 3 and valve 10 of Fig. 2 are standard relief valves such as shown in Vickers Patent No. 2,043,453 issued June 9, 1936.

A pressure conduit 43 leading from pump 5 branches off to the four-way valves 39 and 40 through conduits 44 and 45, respectively. The right hand side of the pilot operated valve 39 is connected to the timing valve 41 by a conduit 46 leading to a port 47. The lefthand side of the valve 39 is connected to the timing valve 42 by a conduit 48 and port 47a. Outlets 50 and 51 from the four-way valve 39 are connected to the left and right ends of the pilot operated valve 40 by conduits 52 and 53 respectively. An outlet conduit 54 leading from the valve 40 is connected to the cylinder 6 by a conduit 55 and to ports 56 and 57a of the timing valves 41 and 42 respectively. An outlet conduit 58 from the valve 40 leads to the low pressure relief valve 37 and also to the ports 57 and 56a of the timing valves 41 and 42.

respectively. Ports 59 and 59a of the timing valves are connected by suitable conduits to the tank 16. An outlet conduit 60 from the valve 40 is also connected to the tank through the adjustable throttle valve 38.

A cross section of the timing valve 41 is shown in Fig. 1. This valve is known as a time delay valve and consists essentially of a hydrostatic or constant flow valve 61, a fixed throttle 62 and a free piston 63. The hydrostatic valve is of the same type as described in my Patent No. 1,982,711, dated December 4, 1934. Assuming the valve to be in set position as shown in Fig. 1, the operation is as follows: Oil under pressure is admitted at port 56 and metered through the hydrostatic flow control valve 61 and the fixed throttle 62 to a chamber 64 behind the piston 63. The piston moves slowly to the left until a port 65 is open to the chamber 64 at which time the relatively greater volume from the unrestricted port 65 forces the piston rapidly to the left thereby opening the port 47 to the chamber 64. Pressure is thus available from the port 65 to the port 47, which is connected to the unit receiving the delayed action, this unit in the present instant being the valve 39.

The valve may be reset by applying pressure at the port 57 which is open to a chamber 66. The piston 63 is then moved to the right until it contacts an adjusting screw 67. A check valve 68 allows displacement of liquid from the chamber 64 during the reset stroke of the piston. A check valve 69 allows displacement of pressure fluid from the actuated unit through the port 47 during the reset stroke.

In the operation: Referring to the circuit of Fig. 3, it will be seen that pressure to or from the cylinder 6 must pass through the pilot operated valve 40. When the piston 7 is being lifted pressure passes from the pump 5 through conduits 43, 45, valve 40, and conduits 54 and 55. A valve 10 similar to that described in connection with Fig. 2, may be placed in conduit 45 to prevent the load from falling in case of power failure during hoisting. During the lowering stroke of the piston 7 pressure passes from the cylinder 6 to the tank through conduits 55 and 54, valve 40, conduit 60 and the throttle valve 38. The rate of the lowering stroke is determined by the setting of the throttle valve 38.

Referring now to the timing cycle, assuming that the ram 7 is being lowered, the pressure lines 43 and 45 are open to the tank through valve 40, conduit 58 and the low pressure relief valve 37. The port 56a of the time delay 42 is also exposed to this low back pressure or pilot pressure. When the time setting of the valve 42 expires as the ram 7 reaches its lower-most position, the port 56a of this valve is open to the port 47a so that pilot pressure is directed through the line 48 to the left hand side of the four-way valve 39. This valve 39 is shifted by this pilot pressure so that pilot pressure from the main pressure line 43 is directed through the conduit 52 to the lefthand side of the four-way valve 40. The latter valve is then shifted so that the delivery of the pump 5 is directed from the conduit 45 to the main cylinder 6 through the conduits 54 and 55, thus causing the ram 7 to be raised.

During the raising stroke of this ram, pilot pressure from the pressure conduit 55 is directed to the port 57a of the valve 42 to reset the same. This pressure is also exerted at the port 56 of the timing valve 41 and starts the delay of this

valve. This delay controls the time during which a constant delivery of pressure fluid is directed from the pump 5 to the main cylinder 6 and thereby controls the length of the stroke of the piston 7. When the time setting of the valve 41 has expired, port 47 of this valve is opened to port 56 so that pilot pressure is directed through the valve 41 in the conduit 46 to the righthand side of the four-way valve 39. The four-way valve 39 is shifted by this pressure so that the pilot pressure from the conduit 44 is directed through the conduit 53 to the righthand side of the four-way valve 40. This valve is in turn shifted so that the main cylinder 6 is open to the tank through conduits 55 and 54, valve 40, conduit 60 and the throttle valve 38 and the ram again starts its lowering stroke.

The relief valve 37 acts at this time to maintain sufficient back pressure to reset the time delay valve 41 and operate the time delay valve 42, the setting of which determines the length of the downward stroke of the main cylinder. As previously described when the setting of the valve 42 has expired the port 56a is open to the port 47a so that the four-way valves 39 and 40 can both be shifted to cause the cycle to repeat.

I claim:

1. In a hydraulic circuit, a timing mechanism for controlling the operation of pilot pressure comprising a pilot valve, means thereon for operating the same comprising a shaft extending therefrom and radial fingers spaced on said shaft, a timing means comprising a cylinder and piston therein, a rod on said piston, spaced dogs on said rod adapted to contact, respectively, the fingers of said pilot valve, a flow control valve means, and valve means for directing pressure to one end or the other of said cylinder and for connecting the other end of said cylinder to said flow control valve means whereby the traverse of the piston in said cylinder is limited in time by the setting of said flow control valve.

2. In a hydraulic system, a double acting motor and means for controlling the same comprising a source of liquid under pressure, a reversible, motor-actuated valve hydraulically connected with said motor and arranged to direct liquid under pressure to one side or the other of said motor, a valve means connected with said source and motor-actuated valve shiftable to cause reversing of said motor-actuated valve, and a tim-

ing cylinder including a shiftable member hydraulically connected with said motor-actuated valve and arranged to be shifted concurrently with said motor, and means operably connecting said member and said valve means whereby shifting of said member effects shifting of said valve means and consequent reversal of said motor actuated valve.

3. In a hydraulic system, a double acting motor and means for controlling the same comprising a source of liquid under pressure, a reversible, motor-actuated valve hydraulically connected with said motor and arranged to direct liquid under pressure to one side or the other of said motor, a valve means connected with said source and motor-actuated valve shiftable to cause reversing of said motor-actuated valve, and a timing cylinder including a shiftable member hydraulically connected with said motor-actuated valve and arranged to be shifted concurrently with said motor, means operably connecting said member and said valve means whereby shifting of said member effects shifting of said valve means and consequent reversal of said motor actuated valve, and means for controlling the rate of flow of liquid from said timing cylinder whereby the operation of said member is time controlled.

4. In a hydraulic system, a double acting motor and means for controlling the same comprising a source of liquid under pressure, a reversible, motor-actuated valve hydraulically connected with said motor and arranged to direct liquid under pressure to one side or the other of said motor, a secondary valve for controlling said motor-actuated valve, a timing cylinder, each end of which is hydraulically connected with said motor-actuated valve, a piston in said timing cylinder to be shifted concurrently with said motor operably connected with said secondary valve whereby a predetermined shifting of said piston in either direction will actuate said secondary valve, a flow control device, and means connecting said flow control device with said motor-actuated valve, whereby the exhaust from said timing cylinder is passed through said flow control valve and said motor-actuated valve is shifted by movement of said secondary valve at predetermined intervals.

HARRY F. VICKERS.
